UNITED STATES PATENT OFFICE.

WILLIAM S. DOLLARD, OF ATTICA, KANSAS.

WRENCH.

1,188,254.

Specification of Letters Patent. Patented June 20, 1916.

Application filed April 11, 1916. Serial No. 90,449.

To all whom it may concern:

Be it known that I, WILLIAM S. DOLLARD, a citizen of the United States, residing at Attica, in the county of Harper and State of Kansas, have invented a new and useful 5 Wrench, of which the following is a specification.

The present invention appertains to wrenches, and aims to provide a novel and 10 improved wrench adapted especially for removing and applying the axle nuts of wagons, buggies, and other vehicles, whereby a nut can be unscrewed and removed without danger of it being dropped, or the hands being 15 coming greasy or dirty, the nut being readily replaced.

It is the object of the invention to provide a wrench of the nature indicated which is 20 comparatively simple, durable and inexpensive in construction, which has novel means for clamping the nut, and which is 25 convenient, practical and efficient in use.

With the foregoing and other objects in view which will appear as the description 25 proceeds, the invention resides in the combination and arrangement of parts and in the details of construction hereinafter described and claimed, it being understood 30 that changes in the precise embodiment of the invention herein disclosed can be made within the scope of what is claimed without departing from the spirit of the invention.

The invention is illustrated in the accompanying drawing, wherein:—

35 Figure 1 is a side elevation of the improved wrench, portions being shown in section and others being broken away. Fig. 2 is a plan view of the wrench, a portion of the screw being broken away. Fig. 3 is a 40 cross section taken on the line 3—3 of Fig. 2.

In carrying out the invention, there is 45 provided a plate 1 forming part of a casting or forging, and which carries the nut socket 2. Said nut socket embodies the three walls 3 and 4 which are preferably integral with the plate 1, and which are U-shaped in section, as seen in Fig. 2. The fourth wall of the socket 2 embodies a plate or jaw 5 to the 50 inner side of which is secured a transverse bar or strip 6 having its terminals formed into trunnions 7 which are pivoted through

the walls 4 adjacent the edges thereof and between the mouth of the socket and plate 1. The plate 5 is thus mounted for rocking 55 or oscillatory movement, to provide means for clamping the nut within the socket.

One end of the plate 1 has an angularly extending flange or lip 8 and a screw 9 is threaded through the flange 8 and wall 3 60 adjacent the plate 1 and projects through the socket adjacent the plate 1, the shank of the screw 9 having a suitable handle 10 remote from the plate 1, while the screw is provided with a reduced portion 11 adjacent its other end and received by an open slot 12 with which the plate 5 is provided adjacent the plate 1. This screw 9 is employed for adjusting the plate or jaw 5, since when the screw 9 is rotated, the end of 70 the plate 5 is moved therewith longitudinally of the plate 1.

The inner end of the plate 1, remote from the flange 8, has a longitudinally projecting shank 13 projecting away from the screw 9, 75 and said shank has a handle 14 at its free end. Riveted or otherwise secured to the plate 1 centrally of the socket 2 is a perpendicular stem 15 upon which is mounted a wooden or equivalent handle 16. 80

To apply the wrench to a nut, the screw 9 is rotated to bring the plate 5 approximately parallel with the wall 3, and the wrench or tool can then be manipulated by the handle 16 for slipping the socket onto 85 the nut, after which the screw 9 is rotated to move the corresponding end of the plate 5 away from the wall 3, as seen in Fig. 1, whereby the outer end of the plate or lever 5 is moved or swung toward the wall 3, 90 to clamp the nut between the plate 5 and wall 3, said plate and wall providing jaws for gripping the nut tightly within the socket. The handles 10 and 14 can then be used for rotating the wrench to unscrew the 95 nut, and when the nut is detached, it will be held tightly within the socket, to prevent the nut being dropped in the dirt or lost. It is unnecessary to handle the nut, thereby eliminating getting the hands 100 greasy or dirty. The nut can be readily replaced and screwed home, as will be apparent.

The present wrench can be used for many

purposes, but is adapted especially for removing and applying the nuts of vehicle axles.

The wrench consists of but few parts, and 5 is not apt to get out of order.

Having thus described the invention, what is claimed as new is:

1. A wrench embodying a plate having a socket, said socket being composed of 10 three walls of U-shape united with said plate and a fourth wall pivotally mounted between a pair of the first mentioned walls, and means extending through the other of the first mentioned walls for swinging the 15 last mentioned wall to clamp a nut within the socket.
2. A wrench embodying a plate having a socket, said socket being composed of 20 three walls of U-shape united with said plate and a fourth wall pivotally mounted between a pair of the aforesaid walls, the last mentioned wall being pivoted between its ends, and means engaged through the other of the first mentioned walls adjacent 25 the plate for swinging the respective end of the last mentioned wall.
3. A wrench embodying a plate having a socket, said socket being composed of 30 three walls of U-shape united with said plate and a fourth wall pivotally mounted between a pair of the aforesaid walls, the last mentioned wall being pivoted between its ends, and a screw engaged through the other of the first mentioned walls and en- 35 gaged with that end of the fourth wall adjacent said plate.

4. A wrench embodying a plate having a nut socket, said socket being composed of three walls of U-shape united with said plate and a fourth wall pivotally mounted 40 between its ends between a pair of the aforesaid walls, the plate having a flange at one end and handle member at its other end, a screw extending through said flange and one of the first mentioned walls and thread- 45 edly engaging one of them, one end of said screw being connected with that end of the last mentioned wall nearest the plate.

5. A wrench embodying a plate having a nut socket, said socket being composed of 50 three walls of U-shape united with said plate and a fourth wall trunnioned between a pair of the first mentioned walls, the last mentioned wall being trunnioned between its ends and that end thereof nearest the plate 55 having an open slot, one end of the plate having a flange, a screw extending through one of the first mentioned walls and said flange and threadedly engaging one of them, the screw having a reduced portion 60 received by said slot, the other end of the plate having a shank, said shank and screw having remote handles, and a handle carried by the plate adjacent the socket.

In testimony that I claim the foregoing 65 as my own, I have hereto affixed my signature in the presence of two witnesses.

WILLIAM S. DOLLARD.
